UNITED STATES PATENT OFFICE.

GOTTHARD HÄFELE, OF BUFFALO, NEW YORK.

DESIGN FOR A COMBINED LAMP PEDESTAL AND STAND.

Application filed February 13, 1923. Serial No. 5,165. Term of patent 3½ years.

To all whom it may concern:

Be it known that GOTTHARD HÄFELE, a citizen of the Republic of Germany, residing at Buffalo, in the county of Erie and State of New York, has invented a new, original, and ornamental Design for Combined Lamp Pedestal and Stand, of which the following is a specification, reference being had to the accompanying drawing, forming part thereof.

The figure is a perspective of a combined lamp pedestal and stand, showing my new design.

I claim:

The ornamental design for a combined lamp pedestal and stand, as shown.

In testimony whereof, I affix my signature.

GOTTHARD HÄFELE.
